**COMBINED VISE AND SAWING GUIDE FOR
TUBING OR THE LIKE**

John D. Benfield, 415 Brainard, Detroit, Mich.

Filed Dec. 4, 1961, Ser. No. 67,783

Term of patent 14 years

(Cl. D54—13)

FIG. 1

FIG. 2

FIG. 3

FIGURE 1 is a front elevation of a combined vise and sawing guide for tubing or the like showing my new design.

FIGURE 2 is a top plan view thereof.

FIGURE 3 is an end elevation thereof as seen from the left of FIGURE 1.

FIGURE 4 is a rear elevation thereof.

FIGURE 5 is a bottom plan view thereof.

FIGURE 6 is an elevation thereof as seen from the opposite end of FIGURE 3.

I claim:

The ornamental design for a combined vise and sawing guide for tubing or the like, as shown.
